H. J. KASTNER

TOY

Filed July 17, 1924

Inventor

Henry Jacob Kastner

33, *H. J. Kastner*
Attorneys

UNITED STATES PATENT OFFICE.

HENRY J. KASTNER, OF DAYTON, OHIO.

TOY.

Application filed July 17, 1924. Serial No. 726,570.

To all whom it may concern:

Be it known that I, HENRY J. KASTNER, a citizen of the United States, residing at Dayton, in the county of Montgomery and State of Ohio, have invented certain new and useful Improvements in Toys; and I do declare the following to be a full, clear, and exact description of the invention, such as will enable others skilled in the art to which it

10 appertains to make and use the same.

My invention relates to improvements in toys and has for its object to provide a simple and inexpensive device which is preferably embodied in such form as to represent 15 a circus "stunt" or "thriller," in which a clown is shot from a cannon and suspended from a remote trapeze which is held by an acrobat on an appropriate support, such as a horizontal bar.

20 With the foregoing in view, the invention resides in the novel subject matter hereinafter described and claimed, the description being supplemented by the accompanying drawing.

25 Figure 1 is a perspective view of the toy. Figure 2 is a vertical sectional view of the cannon.

Figure 3 is a perspective view of the clown.

30 Figure 4 is a detail sectional view on line 4—4 of Fig. 2.

The form of construction selected for illustration, is hereinafter rather specifically described, with the understanding however 35 that such construction constitutes only one embodiment of the invention.

The numerals 1 designate a pair of horizontal base bars beveled at one end and secured by a combined clamping and pivot bolt 1^a against opposite sides of a cannon supporting block 2, which block carries an inclined cannon barrel 3 having a longitudinal slot 4 which opens through its muzzle. The rear end of the barrel 3 is closed, 40 except for a central opening 5 and a longitudinal groove 6 formed in the wall of said opening. Secured to the rear end of the barrel 3, I have shown a wear-plate 7 having a notch 8 alined with the groove 6. A 45 plunger-forming rod 9 passes slidably through the opening 5 and is provided within the barrel 3, with a fixed washer or other shoulder 10 engaged by a coiled compression spring 11, to force the plunger rod forwardly. The rear end of this rod however

is provided with a knob 12 by means of which it may be retracted to compress the spring 11, and a lateral pin 13 is provided on said rod to engage the wear-plate 7 and hold the cannon set, with the spring under 60 compression. When the knob is turned however, to aline the pin 13 with the notch 8 and groove 6, the spring will immediately act to forwardly project the plunger rod.

Adapted for reception in the front end 65 of the barrel 3, when the cannon is set, is a figure 14 which preferably represents a clown, said figure being provided with a hook 15 which extends upwardly therefrom and is receivable in the slot 4. When the 70 cannon is released, the figure 14 is forwardly projected and the hook 15 is intended to engage an elevated support, described below.

From the block 2, the base bars 1 diverge 75 and are connected at their widely spaced ends, by a transverse bar 16. Rising from these ends, I have shown two standards 17 which may be suitably braced as at 18. The upper ends of the standards are connected 80 by a horizontal bar 19 upon which a figure 20 is pivotally hung, said figure representing an acrobat. This figure supports a wire loop 21 which simulates a trapeze, and such loop is at the proper elevation, so that when the 85 figure 14 is projected from the cannon barrel 3, the hook 15 will engage it, thus suspending the figure 14 in mid-air and effectively representing a clown performing a circus "stunt" or "thriller". Obviously, by 90 loosening the bolt 1^a, the cannon 2 may be tilted for sighting and then secured in place.

The device is extremely simple and inexpensive, as it may be constructed almost entirely of wood. Nevertheless, it is a very 95 desirable and amusing toy which may be manufactured in an attractive manner, particularly, when attractively painted in gaudy colors.

The part indicated at 22 is merely a cord 100 connected with the figure 14 and with one of the standards 17, to prevent movement of said figure beyond a predetermined distance, should it fail to catch upon the trapeze 21.

I claim:

1. A toy comprising an elevated support, a figure toy pivoted thereon, a trapeze suspended from said toy, a projecting device spaced from the trapeze, and a figure toy receivable within said device to be projected 110

thereby toward the trapeze, said projectible toy having means to catch said trapeze when projected into engagement therewith.

2. A toy comprising a simulation of an acrobat suspending a trapeze, means for supporting said simulation, a gun spaced from the trapeze, and a figure toy receivable within the gun to be projected thereby toward the trapeze, said toy having means to engage said trapeze to support the former.

3. A toy comprising a support having a horizontal bar, a figure toy pivoted on said bar, a trapeze suspended from said toy, a projecting device spaced from the trapeze, and a figure toy receivable in said device to be projected therefrom, said projectible device having means to catch said trapeze when projected into engagement therewith.

4. A toy comprising a simulation of an acrobat suspending a trapeze, means for supporting said simulation, a gun spaced from the trapeze, and a figure toy receivable within the gun to be projected thereby to-

ward the trapeze, said toy having an upstanding hook to engage said trapeze to support the former.

5. A toy comprising a base, a gun mounted on one end of said base, standards rising from the other end of the base, a horizontal bar extending between said standards, a simulation of an acrobat hung from said bar, a miniature trapeze suspended from said simulation, a figure toy adapted for reception in the gun to be projected by the latter toward the trapeze, and an upstanding hook carried by said figure toy for engagement with said trapeze.

6. A structure as specified in claim 1, together with base bars carrying said support, a gun-carrying block between said bars, and a combined pivot and clamping bolt passing through said bars and block.

In testimony whereof I have hereunto affixed my signature.

HENRY J. KASTNER.
